UNITED STATES PATENT OFFICE.

BENJIMAN MILEY, OF WALLA WALLA, WASHINGTON, ASSIGNOR TO WALTER COYLE,
OF WALLA WALLA, WASHINGTON.

KNIFE-GAGE.

1,059,894.

Specification of Letters Patent. Patented Apr. 22, 1913.

Application filed May 29, 1912. Serial No. 700,470.

To all whom it may concern:

Be it known that I, BENJIMAN MILEY, a citizen of the United States, residing at Walla Walla, in the county of Walla Walla, 5 State of Washington, have invented certain new and useful Improvements in Knife-Gages; and I do hereby declare the following to be a full, clear, and exact description of the invention, such as will enable others 10 skilled in the art to which it appertains to make and use the same.

This invention relates to improvements in knife gages, and has for its principal object to provide a gage by means of which 15 strips of leather or other material may be easily cut.

Another object of the invention is to provide a gage of the character described by means of which strips of different widths 20 may be cut.

A further object of the invention is to provide a gage for the purpose described which is of such construction as to permit 25 of a knife being instantly removed or attached thereto.

A still further object of the invention is to provide a knife gage of the character described which is of such construction as to frictionally engage the leather during its 30 movement therewith, whereby said gage will be held in engagement with the leather without the necessity of the operator other than bearing his thumb upon the gage.

A still further object of the invention is 35 to provide a gage of the character described which is composed of a relatively few number of parts, is therefore simple in construction and is cheap to manufacture.

With these and other objects in view, the 40 invention consists in the construction and novel combination of parts hereinafter fully described, illustrated in the accompanying drawing and pointed out in the claims here-to appended; it being understood that various changes in the form, proportion, size 45 and minor details of construction within the scope of the claims may be resorted to without departing from the spirit or sacrificing any of the advantages of the invention.

In the drawing: Figure 1 is a perspective view showing the application of a knife gage constructed in accordance with my invention, Fig. 2 is an enlarged vertical longitudinal sectional view therethrough, Fig.

3 is an elevation of one end of the gage, Fig. 4 is an elevation of the other end of the gage, Fig. 5 is a horizontal sectional view taken on the line 5—5 of Fig. 2, and Fig. 6 is a perspective view of the clamping 60 plate.

Like reference numerals designate corresponding parts in all the figures of the drawing.

Referring to the drawing, my improved 65 gage is indicated as a whole by the reference letter A. This gage comprises a body which is formed from a pair of flat metal plates 5—5 of uniform size, one end portion 6 of each plate being bent at right angles and 70 disposed against each other to form a guide and consequent upper and lower plates 7 and 8 respectively. The end walls 6 are connected together by means of set screws 9—9 or other suitable means, and these walls 75 are respectively formed with centrally disposed registering openings 10—10.

A clamping plate 11 is disposed between the upper and lower plates 7 and 8, and projecting from one end thereof is a head 12 80 which is connected to the plate by a neck 13, said neck riding in the registering openings 10 and the head being disposed beyond the end walls 6. By means of this construction the clamping plate 11 is capable of 85 moving toward or away from the lower plate 8, and at same time is prevented from any longitudinal or lateral movements.

In order to yieldably hold the clamping plate 11 toward the bottom plate 8, there 90 is provided a U-shaped guide pin 14, the legs 15—15 thereof sliding in suitable openings formed in the top plate 7 and have their lower ends connected centrally to the clamping plate 11. Disposed around each leg 15 95 intermediate the plate 11 and the upper plate 7 is a coil spring 16 which tends to normally urge the clamping plate 11 toward the bottom plate 8. It will be observed that the bight of the guide pin 14 extends above 100 the upper plate 7 to form a finger-piece.

Formed in the upper and lower plates 7 and 8, and the clamping plate 11 is a series of spaced transverse knife-receiving openings 17. The respective openings of the 105 plates are arranged in registration for permitting a knife blade being readily inserted thereinto.

In practice, a strip of leather B or the like is inserted between the lower plate 8 110

and the clamping plate 11. The gage is held to the strip B by means of the spring 16 as explained above. The point of a knife blade C is then inserted through any of the 5 registering openings 17 of the gage. The gage is then shifted along the strip B, and the operator exerts a constant pressure upon the knife C. As a result, a strip of leather is sliced off the main strip, the width of 10 the slice depending upon which opening 17 is employed as will be readily understood.

What is claimed is:

1. In a knife gage, the combination with 15 a pair of spaced flat plates each having one end portion bent inwardly, said portions being secured together to form a guide and conjointly formed with a centrally disposed opening, a clamping plate disposed intermediate said plates and having a headed 20 projection formed on one end and having its neck engageable within the opening of the guide, and means for yieldably holding the clamping plate against spreading with respect to one of said plates, one of said 25 plates and the clamping plate being formed with knife-receiving openings.

2. In a knife gage, the combination with

spaced upper and lower flat plates respectively each having one end portion bent inwardly, said portions being secured together to form a guide and conjointly formed with a centrally disposed opening, a clamping plate disposed intermediate said plates and having a headed projection formed on one end and engageable within 30 the opening of the guide, the upper plate being formed with a pair of spaced openings, a U-shaped guide pin having its legs extending through said openings, said legs having rigid connection at their ends with 35 said clamping plate, coil springs respectively arranged around the legs of the pin intermediate the clamping plate and the upper plate to yieldably urge said clamping plate toward the bottom plate, said 40 upper plate and clamping plate being formed with registering knife-receiving openings.

In testimony whereof, I affix my signature, in presence of two witnesses.

BENJIMAN MILEY.
